UNITED STATES PATENT OFFICE

WALTER L. MACK, OF TOLEDO, OHIO, ASSIGNOR, BY MESNE ASSIGNMENTS, TO AIR-WAY ELECTRIC APPLIANCE CORPORATION, OF TOLEDO, OHIO, A CORPORATION OF DELAWARE

RADIATOR CONSTRUCTION

Application filed October 16, 1929. Serial No. 400,021.

The present invention relates to the construction of radiators, particularly radiators of the type wherein the capacity is greatly increased by a forced circulation of air over the surface thereof. It is one of the objects of the invention to produce such a radiator which shall be simple and inexpensive to manufacture and strong in construction. It is also an object of the invention to obtain such a device which will utilize material of high heat conductivity, and which will at the same time be free from porosity and blow holes and any tendency to leak.

While one of the chief applications of the invention may be in connection with steam heating radiators, it may also be employed with hot water radiators or with any heating medium or in any situation where it is desired to transmit heat to the surrounding air or other gas from a heating medium occupying the interior of the radiator. The device is also adapted to be used for cooling air in which case the interior of the radiator may be filled with a refrigerant such as ammonia or sulphur dioxide.

In general the invention is adaptable for use in any environment where the surrounding air or gas is to be either heated or cooled, in other words, for use anywhere that heat is to be transmitted through the radiator, either inwardly or outwardly.

In order to more clearly explain the invention, reference is made to the following description of different embodiments thereof taken in connection with accompanying drawings in which

Fig. 1 is a side elevation partly in section of a heating device employing a radiator of improved construction;

Fig. 2 is a sectional plan of the radiator shown in Fig. 1;

Fig. 3 is a side elevation of one of the radiator units partly broken away to show the interior construction;

Fig. 4 is a horizontal section of one of the radiator units taken on the line 4—4 of Fig. 3;

Fig. 5 is an enlarged sectional view of the small end of the duct shown in Fig. 4;

Fig. 6 is an enlarged sectional view of the cross bracing shown in Fig. 4;

Fig. 7 is a top perspective view of the inner duct or lining showing an inlet pipe bushing in place;

Fig. 8 is a front elevation partly in section of another form of radiator construction; 55

Fig. 9 is a section taken on the line 9—9 of Fig. 8, and

Fig. 10 is a section similar to Fig. 4 of still another form of radiator unit.

Referring to the drawings more in detail, 60 11 represents an enclosing box in which there may be positioned a radiator having a plurality of units 12, 13, 14 and 15. At the front of the box there are shown a plurality of adjustable louvers 16, which control the amount 65 and direction of the air being discharged through the radiator. At the rear of the radiator is shown a blower or fan 17 for positively circulating air over the surface of the radiator. Each radiating unit may be supplied 70 with steam or other heating medium through an orifice 18 connected with a supply pipe 19. These supply pipes are connected by a header, which in turn is supplied from a main steam pipe 21.

In a similar manner orifices 22 for the outflow of the condensed steam are connected with discharge pipes 23, which are connected with a discharge header 24, the discharge header connecting with a main discharge pipe 25. 80 A suitable motor 26 for driving the fan 17 may have supporting pipes or tubing 27 and 28, which are connected by means of pipe fittings 29 and 30 to the inlet and discharge steam pipes 21 and 25.

Each heating unit is preferably provided with a duct 29 for the steam or other heating medium, and is surrounded with a plurality of fins 30 extending substantially at right angles to the wall of the duct 29. As 90 shown in Figs. 2 and 4 the ducts 29 are so formed that the width is less on the side of the radiator where the air is discharged than it is on the fan side. This leaves an air passage of greater cross sectional area where the heated air is being discharged than on the side where the air is entering the radiator. Inasmuch as air expands and occupies a greater space when it is heated, this increasing of the area of the discharge passage 95 100

for the air as it becomes hotter is desirable, and in accordance with the laws governing the combined heating and circulating of the air.

- 5 The duct or compartment 29 may preferably have an inner lining of sheet metal, such as stainless steel. Side walls 31 may be formed first, one way as shown in Fig. 5, being to bend a sheet of such material in 10 the form of a tapered duct of relatively small width and welding the joined edges as indicated at 32. Another way of forming this portion of the lining is to bend the tube having the correct perimeter into the desired 15 shape without using the longitudinal weld 32. The end openings of the compartment 29 may be closed by end plates 33, which have secured therein bushings 34 which may be threaded as at 35 for the inlet and outlet 20 pipes 19 and 23. The bushings 34 may be secured to the end plates by welding as indicated at 35, and by similar welding 36, the end plates may be secured to the side walls 31. It is also desirable to provide cross braces 25 37. One way of forming such cross braces is to punch indentations 38 in the side walls 31, grind off the tops 39 of the indentations, or otherwise true them up, and finally drive a tightly fitting sleeve 40 into the alined openings (Fig. 6). This sleeve 40 may if desired 30 be welded in place as indicated at 40^a.

The whole compartment formed of sheet metal, which is to be the lining of the completed radiator unit, together with the bushings 34, is then used as a core of a cast metal mold, and an enclosing shell 41 of suitable material is cast around the lining. A plurality of parallel fins 30 extending substantially perpendicularly to the wall 31 of the lining 35 are preferably cast integral with the shell 41, and provide greatly increased radiating surface. The outer shell 41 is preferably of a high heat conductivity. It is also desirable that this outer shell be of a character that 40 is not brittle, but will permit a considerable amount of deformation without breaking. Among the materials which meet the foregoing requirements may be mentioned, for example an alloy comprising 87% aluminum and 13% silicon. During the operation of 45 pouring, the foregoing alloy may be modified by the addition of a small amount of metallic sodium.

The form of radiator shown in Fig. 8 comprises a pipe or tube 46 of sheet metal, such as stainless steel, to each end of which there may be welded, or otherwise suitably secured a tapped bushing 47 for connection with inlet and exhaust pipes. The tubing 46 with the 50 end bushings 47 is used as a core of the mold, and an enclosing shell 48 is cast around the core so that the tubing becomes a lining embedded in the surrounding material. The outer shell preferably has formed integral 55 and extending outwardly in a direction sub-

stantially perpendicular to the walls of the tubing a plurality of radiating fins 49. The inner lining renders the construction stronger, less porous and more resistive to corrosive action of the steam. The outer shell is preferably of material having a high heat conductivity. 70

In Fig. 10 is shown a radiator unit in which the width of a compartment 51 for the heating medium is tapered toward both the incoming and outgoing air with the greatest thickness near the middle. This may be constructed as in Fig. 4 with an inner lining 52 of sheet metal embedded in the outer shell 53, which is cast around the lining 52 as a 80 core, and which is provided with a plurality of fins 54. The incoming air first passes through a broad passage as indicated at the arrow A and then through a narrower passage as indicated at the arrows B, and finally is discharged where the passage is again broad as at the arrow C. While not necessarily confined thereto, the conformation just described is adapted for use where the air is being cooled by a refrigerating medium 85 within the radiator, and is particularly suitable for such a radiator which is used sometimes for heating and sometimes for cooling. 90

It is to be understood that the hereinbefore described embodiments of invention are for the purpose of illustration only, and not by way of limitation as various changes may be made therein without departing from the sphere and scope of the invention as defined 100 in the subjoined claims.

I claim:

1. A radiator comprising an inner duct of sheet metal having a stream line contour and an enclosing casing of cast metal, said 105 casing having radiating fins extending substantially perpendicularly to the wall of said duct.

2. A radiator comprising a sheet metal compartment having side walls bent into a 110 stream line conformation and sheet metal end walls welded to the side walls, inlet and outlet pipe bushings welded in said end walls, and an outer cast metal casing surrounding 115 said compartment and having integral fins extending in a direction substantially perpendicular to the walls of said compartment.

3. A radiator comprising a stream lined inner duct of sheet metal and an enclosing shell 120 of cast metal, said enclosing shell having fins disposed substantially perpendicularly to the wall of said inner duct in order to greatly strengthen the pressure resistance of the inner duct by forming outside stays holding the inner duct to its original form when a 125 pressure is exerted inside the inner duct.

4. A radiator comprising a relatively wide and flat inner duct of sheet metal and an enclosing shell of cast metal having radiating 130 fins disposed substantially at right angles to

the axis of said duct, said fins extending entirely around said duct, and being wider at the sides of the duct than across the edges thereof.

- 5 5. A radiator comprising a relatively wide and flat inner duct of sheet metal including opposed side walls provided with registering inwardly punched indentations, and an enclosing shell of cast metal including integral-
- 10 10. ly cast radiating fins and integrally cast bridge lugs flowed through said registering indentations.
- 15 6. A radiator comprising a relatively wide and flat inner duct of sheet metal formed with two longitudinal edges welded together to form a seam at the longitudinal edge of the duct and an enclosing shell of cast metal including integral fins, said shell including a longitudinal bead enclosing said seam.
- 20 7. A radiator comprising an inner duct of sheet metal having side walls and end walls welded thereto, a threaded bushing welded into an end wall, and a shell of cast metal enclosing said side walls, said end walls and
- 25 25. said bushing, said shell including integral fins.
- 30 8. A radiator comprising a relatively wide and flat inner duct of sheet metal including side walls, lugs bridging the space between said side walls to resist collapsing thereof and an enclosing shell of cast metal including integral fins positioned to brace the side walls against expansive pressures from within the duct.
- 35 35. Signed by me this 14th day of October, 1929.
